H. RUPPEL,
BLUE FLAME WICK-OIL BURNER,
APPLICATION FILED DEC. 3, 1914.

1,159,101.

Patented Nov. 2, 1915.

UNITED STATES PATENT OFFICE.

HENRY RUPPEL, OF CLEVELAND, OHIO, ASSIGNOR TO AMERICAN STOVE COMPANY, OF ST. LOUIS, MISSOURI, A CORPORATION OF NEW JERSEY.

BLUE-FLAME WICK OIL-BURNER.

1,159,101.

Specification of Letters Patent.

Patented Nov. 2, 1915.

Application filed December 3, 1914. Serial No. 875,321.

To all whom it may concern:

Be it known that I, HENRY RUPPEL, a citizen of the United States, residing at Cleveland, in the county of Cuyahoga and State 5 of Ohio, have invented certain new and useful Improvements in Blue-Flame Wick Oil-Burners, of which the following is a specification, reference being had therein to the accompanying drawing.

16 My invention relates to improvements in blue flame wick oil burners.

The object of my invention is to provide a burner of this character in which the supporting means for the perforated combustion section also serves as a means for regulating the upward movement of the wick.

A still further object of my invention is to provide a simple, cheap and more effective burner of this character having certain details of structure and operation hereinafter more fully set forth.

In the accompanying drawings—Figure 1 is a vertical sectional view taken through my improved burner and showing the perforated combustion section thereon. Fig. 2 is a top plan view of Fig. 1, with the combustion section removed. Fig. 3 is a bottom perspective view of the combined combustion section, supporting ring and wick stop.

30 Referring now to the drawings, 1 represents the inner wick tube of my improved burner, and 2 the outer wick tube, which are arranged some distance apart and between which is vertically movable the wick 3, all of which is well understood by those skilled in the art and needs no further description. The outer wick tube 2, adjacent its upper end has a ring 4 secured thereto by indenting the metal and provided at its upper end with an outwardly extending horizontally arranged flange 5. The outer end of this flange 5 is turned downwardly, as indicated at 6, and provided on opposite sides with the cut-away portions 7, the purpose of 45 which will be later described.

Secured to the inner face of the inner wick tube 1, adjacent its upper end is a ring 8, having at its upper end the outwardly extending annular flange 9. Resting upon the annular flange 9, is an annular ring 10, having its outer edge turned upwardly, as indicated at 11, forming a flange for the purpose hereinafter described. The inner edge of the annular ring 10 is provided with ears 55 12, which are bent downwardly around the

flange 9 of the ring 8, and whereby it is securely fastened thereto. The upper edge of the upwardly turned portion of the ring 10 terminates at a point in a horizontal alignment with the said wick tube. 60

Resting upon the upper face of the flange 5, is a ring 15, which is slightly bent downward and has its outer edge provided with an upwardly extending annular flange 16, which is drawn inwardly at a slight angle, as is shown in Fig. 1 of the drawings. The ring 15 is provided with a series of openings 17, for supplying the space 18 between the outer perforated combustion tube 19 and the shell 20 with air, as is well understood. The 70 inner end of the ring 15 has an upwardly extending flange 21, which has at its upper edge the upwardly extending wick-engaging members 22. These wick-engaging members 22 are arranged at equal distance apart 75 around the flange 21 and extend some distance above the upper end of the outer wick tube 2. The upper ends of these wick-engaging members 22 are pointed and turned inwardly, as indicated at 23, and extend over 80 the space between the inner wick tube 1 and the outer wick tube 2, so as to be in the path of travel of the wick 3 and engage the upper edge of the wick and limit the upward movement thereof. These members 23 are made 85 pointed for the purpose of providing the proper surface for engaging the wick and limiting the upper movement thereof and yet not to cover too much of the wick and prevent an uneven burning thereof. The 90 outer perforated combustion tube 19 rests upon the ring 15, at a point adjacent the upwardly extending flange 21, as clearly shown in Fig. 1 of the drawings.

The lower face of the ring 15 is provided 95 with two oppositely arranged members 24, which extend downwardly and inwardly and adapted to enter the oppositely arranged cut-away portions 7 of the flange 5, and when the ring is turned they travel around 100 upon the lower edge of the downwardly turned portion 6 of the flange 5 and lock the ring 15 thereto. By this structure it will be seen that the ring 15 is readily removable for the purpose of removing or cleaning the 105 wick 3 when necessary.

The inner wick tube 1, is provided with a transverse plate 25 having an opening 26 therethrough and through which extends a vertically disposed rod 27, which is sup- 110

ported at its lower end in the burner and extends some distance above the upper end of the wick-tubes. Loosely mounted upon the upper end of the rod 27 is a skeleton frame 28, which is adapted to support the combustion tubes by means of the ring 29, carried by the inner perforated tube 14, all of which is well understood and a description of the operation thereof is not thought necessary.

From the foregoing description it will be seen that I provide a simple and effective means for supporting the combustion section and at the same time providing the said supporting means with wick stops to limit the upward movement of the wick 3, and at the same time providing means whereby the said wick stops and supporting ring can be readily removed for removing or renewing the wick when necessary.

Having thus described my invention, what I claim and desire to secure by Letters Patent is:

1. A burner of the character described, comprising an inner and an outer wick tube, a flange supported by the outer wick tube below its upper end, a ring removably secured to the flange and adapted to support a combustion section, and inwardly extending wick engaging members carried by the ring and extending over the space between the inner and outer wick tubes.

2. A burner of the character described, comprising an inner and an outer wick tube, a flange carried by the outer wick tube below its upper end, a ring removably secured to said flange and adapted to support a combustion section, upwardly extending wick engaging members carried by the inner edge of the ring and having inwardly and horizontally arranged pointed ends extending over the space between the inner and outer wick tubes.

3. A burner of the character described, comprising an inner and an outer wick tube, a flange carried by the outer wick tube below its upper end, a ring resting upon the flange and adapted to support a combustion tube, said flange having oppositely arranged cut-away portions, inwardly extending members carried by the ring and adapted to pass through the cut-away portions in the flange and locking the ring to the flange, upwardly

extending wick engaging members formed integral with the ring and having inwardly extending horizontally arranged pointed ends extending over the space between the inner and outer wick tubes.

4. A burner of the character described, comprising an inner and an outer wick tube, a horizontally arranged flange secured to the outer wick tube below its upper end and having a downwardly extending outer edge, said flange having oppositely arranged cut-away portions, a ring resting upon the upper face of the flange and slanting downwardly and provided with openings and having its outer edge turned upwardly, inwardly and downwardly extending members carried by the lower face of the ring and adapted to pass through the cut-away portions of the flange and engage the lower edge of the downwardly turned portion of the flange and lock the ring thereon, upwardly extending wick stops formed integral with the ring and extending above the upper edge of the outer wick tube and having pointed horizontally arranged ends extending inwardly over the space between the outer and inner wick tubes.

5. A burner of the character described, comprising an inner and an outer wick tube, a horizontally arranged flange carried by the inner wick tube and adapted to support an inner combustion tube, a horizontally arranged flange carried by the outer wick tube below its upper end and having oppositely arranged cut-away portions, a ring supported by the horizontally arranged flange and slightly bent downwardly and having an obliquely arranged upwardly extending flange at its outer edge, members carried by the lower face of the ring and adapted to pass through the cut-away portion of the flange and engaging the lower face thereof for locking the same to the flange, and upwardly extending pointed wick stops carried by the inner edge of the ring and turned inwardly over the space between the inner and outer wick tubes.

In testimony whereof I hereunto affix my signature in the presence of two witnesses.

HENRY RUPPEL.

Witnesses:

E. T. BUTLER,
C. R. CARUTH.
